(57) **CLAIM**

The ornamental design for a pump shroud, as shown and described.

DESCRIPTION

FIG. 1 is an isometric view of a pump shroud showing our new design.

FIG. 2 is a front plan view of the pump shroud;

FIG. 3 is a rear plan view of the pump shroud;

FIG. 4 is a left side view of the pump shroud;

FIG. 5 is a right side view of the pump shroud;

FIG. 6 is a top plan view of the pump shroud;

FIG. 7 is a bottom plan view of the pump shroud; and,

FIG. 8 is an isometric view of a second embodiment of the pump shroud of the present invention.

Those portions of the drawings shown in broken lines are included for illustrative purposes only and form no part of the claimed design.

CERTIFICATE OF CORRECTION

PATENT NO. : D682,886 S
APPLICATION NO. : 29/421617
DATED : May 21, 2013
INVENTOR(S) : Mark Francis Haider et al.

Page 1 of 1

It is certified that error appears in the above-identified patent and that said Letters Patent is hereby corrected as shown below:

On the title page, Item Description, delete “FIG. 1 is an isometric view of the pump shroud of the present invention mounted to a pump assembly” and insert in place thereof -- FIG. 1 is an isometric view of a pump shroud showing our new design. --

On the title page, Item Description, delete “FIG. 2 is a front plan view of the pump shroud;”

On the title page, Item Description, delete “FIG. 3 is a rear plan view of the pump shroud;”

On the title page, Item Description, delete “FIG. 4 is a left side view of the pump shroud;”

On the title page, Item Description, delete “FIG. 5 is a right side view of the pump shroud;”

On the title page, Item Description, delete “FIG. 6 is a top plan view of the pump shroud;”

On the title page, Item Description, delete “FIG. 7 is a bottom plan view of the pump shroud; and”

On the title page, Item Description, delete “FIG. 8 is an isometric view of a second embodiment of the pump shroud of the present invention.”

Signed and Sealed this
Twenty-fourth Day of June, 2014
